UNITED STATES PATENT OFFICE.

JAMES C. MEEM, OF BROOKLYN, NEW YORK, ASSIGNOR OF ONE-HALF TO FREDERICK L. CRANFORD, OF BROOKLYN, NEW YORK.

SECTIONAL SHEATHING.

1,246,135.

Specification of Letters Patent.

Patented Nov. 13, 1917.

Application filed September 21, 1915. Serial No. 51,740.

To all whom it may concern:

Be it known that I, JAMES C. MEEM, a citizen of the United States, residing at Brooklyn, in the county of Kings and State of New York, have invented certain new and useful Improvements in Sectional Sheathing, of which the following is a full, clear, and exact specification.

This invention relates to apparatus for sheathing an excavation to prevent caving in while a foundation, pier, footing, or other structure, is being erected therein. The invention is more particularly an improvement upon the apparatus disclosed in my application filed May 9, 1914; Serial No. 837,373, and is intended for use in connection with the method therein disclosed.

The sheathing sides are inclined to each other and connected by corner blocks or guides as in the prior application, but this invention differs from that disclosed in the prior application in the manner of separably connecting one section with another, and the detailed construction of the sides and corner guides. The sides and guides of this invention are constructed of standard plates and shapes, so that the initial cost is reduced and it is possible to provide a variety of sizes without requiring expensive patterns, jigs, or the like.

The sides are composed of flat sheets with forks or grooves at opposite ends for engaging the guides, and may also be stiffened longitudinally. The guides are formed of plate stampings, having opposite wings bent to engage in the grooves of the sides, and between the bent wings are slotted guide plates to receive short keys which co-operate to guide and position the corner guide of the adjoining section. These keys not only have the function of connecting the guides of one section with the guides of the adjoining one, but also serve to position the guides for the next section to be erected relatively to the guides of an already erected section so that the sides for the next section will be certainly guided in the proper direction parallel to the sides previously set. It is essential to hold the wings of the corner plates rigid in order that the sides may be readily slid thereon to their proper position, and the problem is to secure this result without either an initially expensive construction and without preventing the structure from being knocked down

when it has served its purpose. Thus it is insured that sheathing for excavations of considerable depth or length will not deviate, and that the sections will all be relatively rigid. I prefer to use short sections of standard I-beams as keys for connecting one guide with another. As shown herein, the guides are provided on the outside at the upper edge and on the inside at the lower edge with slotted yokes, spaced sufficiently from the surfaces of the guides so that the flanges of the I-beams will slide therein, the web of the key sliding in the slots. The flanges of the keys when engaged with the slotted yokes thus form a rigid arrangement which prevents canting or tilting of the guide, and thereby the sides can be driven where necessary without the liability of disturbing the position of the guides. If the guides move or tilt it becomes difficult to slide the sides to their intended positions.

In the accompanying drawings, Figure 1 is a plan view of a sheathing embodying the invention;

Fig. 2 is a side elevation partly in section; Fig. 3 is a vertical section on the lines 3—3 of Figs. 1 and 4 showing the manner of interlocking the guides by the keys, and the engagement of the sides with the guides;

Fig. 4 is an elevation of one of the guides looking outwardly, and

Fig. 5 is a cross-section on the line 5—5 of Fig. 3.

1 represents the sides which are preferably provided with an angle iron stiffener 2 riveted thereto by rivets 3. At each inner end of the sides 1 are fastened spacing blocks 4 and plates 5 to form a groove 6 to slidably receive the wings of the pyramidal corner connecting guide, block, or plate. The external faces of the sides are thus smooth so as to drive and pull more easily. Each corner guide consists of an intermediate portion 8 having laterally bent inclined wings 9, the wings 9 being broader at the bottom than at the top, as shown in dotted lines Fig. 4. When the wings 9 are bent relatively to the intermediate portion 8 to be approximately at ninety degrees to each other as shown in Fig. 1, the lower edges of the wings 9 and the lower edge of the intermediate portion 8 will be in approximately the same plane, as shown for example in Figs. 3 and 4, but the intermediate

portion 8 will be of greater length than the height of sides 1, as shown in Figs. 3 and 4. The upper edges of the wings 9 will be inclined, as shown in Figs. 3 and 4 so as to assist in guiding the sides. The lower portion of the corner guides will be wider than the upper portion, and the edges of the wings 9 will, when in proper position, be approximately parallel to the edges of sides 1. On the outer upper end of the intermediate portion 8 of each corner guide is fixed a plate 11 having a downwardly opening slot 12, this plate being separated from the external upper surface of the intermediate portion by spacers 13, the plate 11 and spacers 13 being secured by rivets 14. The exterior plates 11 having the downwardly opening slots 12 are longer than the interior plates 16 having the upwardly opening slots 17. The purpose of this is to insure that when the corner guides are driven downwardly for the lower section, they will be accurately guided in the proper inclined direction by the key 20. Also, this assists withdrawal. On the lower inside surface of the intermediate portion 8 are provided similar plates 16 having upwardly opening slots 17 spaced from the intermediate portion by spacers 18 and fastened by rivets 19. 20 represents the key, which preferably consists of a short standard I-beam section having a web to slide in the slots 12 and 17, and flanges whose thickness about corresponds with that of the spacers 13 and 18. The width of the slots 12 and 17 about corresponds with the thickness of the web of the key, so that the key can be slid between the plates 11 and 16. It will thus be seen that the corner plate supports the key, and the key in turn supports the next lower corner plate.

It being remembered that the excavation is to be sheathed as it progresses downward, the first step is to position the upper sheathing section consisting of three or more sides and connecting guides. When this section is partially excavated, the next step is to insert the keys 20 in the plates 21, on the inside of the excavation. The next step is to either drive or excavate at the corners sufficiently to receive the guides for the next section below. The keys being held from further downward movement in the slots 17, the next lower guides are simply hung thereon, and owing to the prescribed fit of the flanges of the keys between the slotted plates 11 and the outer surface of the guides, it will be seen that when the latter are forced downward as far as they can go, they necessarily must travel in the predetermined inclined direction without deviation. Owing to the slots 12 and 17 being parallel one key is necessarily parallel with the one immediately above, and the keys at the several corners will necessarily take the proper posi-

tions. Having positioned the keys and the corner guides carried thereby, the next step is to drive the sides downwardly and outwardly in planes determined by the slope of the corner plate wings 9. As shown in Fig. 1, the grooves in the ends of the sides may be somewhat wider than the thickness of the wings 9, and the wings 9 need not necessarily be precisely parallel to the sides 1, but any looseness will be taken up by the outside earth pressure when the sides have been completely driven. In the case of excavations in wet or moist soils where calking would be desired it is only necessary to calk, grout or concrete the spaces between the lower edge of one side and the upper edge of the next lower side, which is not a matter of any difficulty.

After the excavation has been made to the desired depth, the sheathing can be withdrawn as the foundation is erected therein, or it can be left there. Soft concrete or grout will flow into the spaces left by the sides and corners and prevent any displacement of surrounding earth. If the sheathing is to be recovered, the withdrawal of the lowest tier of sides enables the guides for this tier to be slid off from the lowest keys, leaving the keys supported by plates 16. Then the keys are withdrawn from these plates and the next section above knocked down in the same manner. If it is not desired to recover the deepest part, it is only necessary to cut through the slots 12 above the keys 8 from within the excavation, at the top of the section which is to be left in. Then the upper sections can be separated and removed in the described manner. By inclining the sides, in combination with inclined or pyramidal corner guides, the excavation does not narrow as it increases in depth, but obviously the invention is not restricted to this form, as pits may be sheathed by this invention which narrow or widen at the bottom, as may be desired. This will be done by changing the inclination of the guide wings and varying the lengths of the sides accordingly. Also the invention may be used in horizontal or inclined tunnel or sheathing work without departure from its principle.

The invention has been found especially useful in underpinning existing buildings during subway construction, and in carrying down footings for columns, piers, or the like, but it will be understood that the invention is capable of wide application for other purposes. By this invention excessive excavation is avoided, and also displacement of the surrounding ground. It will also be understood that the number of sides forming the inclosure for a section may be varied, and that the invention might also be employed in trench or tunnel sheathing without departing from its principle.

Having thus described my invention, I declare that what I claim as new and desire to secure by Letters Patent, is:—

1. A sectional sheathing comprising corner guides having inclined wings, sides between said guides engaging opposite sides of said wings, guide plates on opposite sides of each guide, and means engaging the inner guide plate of one guide and the outer guide plate of another guide for positioning adjoining sections.

2. A corner guide for a sectional sheathing comprising a plate having wings, said plate having means on the inner side adjacent the bottom, and on the outer side adjacent the top, for interlocking respectively with guides below and above.

3. The combination with a corner guide comprising an inclined plate having angularly bent inclined wings, of inclined slotted guide yokes oppositely mounted on said plate adjacent the ends thereof, sides engaging said wings, and I-beam keys slidable in said slotted yokes.

4. Sectional sheathing for a prismatic excavation, comprising a series of plate like corner members along each corner of the excavation, and a series of plate like side members along each side of the excavation, the ends of the side members slidably engaging the edges of the respective corner members, and both the corner members and the side members being inclined substantially alike to the axis of the excavation.

5. Sectional sheathing for a prismatic excavation, comprising a series of plate like corner members along each corner of the excavation, each corner member being coupled with the adjacent corner members in the same series, and a series of plate like side members along each side of the excavation,

the ends of the said members slidably engaging the edges of the respective corner members, and both the corner members and the side members being inclined substantially alike to the axis of the excavation.

6. Sectional sheathing for a prismatic excavation, comprising a series of plate like corner members along each corner of the excavation, means slidably connecting each corner member with the adjacent corner members in the same series, and a series of plate like side members along each side of the excavation, the ends of the side members slidably engaging the edges of the respective corner members, and both the corner members and the side members being inclined substantially alike to the axis of the excavation.

7. In combination, a series of corner guides for sectional sheathing for a prismatic excavation, each such guide being slightly inclined to the axis of the excavation and having slidable engagement with adjacent corner guides of the same series, stops to limit the relative slidable extension movement of adjacent corner guides, and side members engaging said corner guides.

8. In combination a series of corner guides for sectional sheathing for a prismatic excavation, each such guide being slightly inclined to the axis of the excavation and having means on the inner side adjacent to the bottom and on the outer side adjacent to the top for interlocking respectively with guides below and above and side members engaging said corner guides.

In testimony whereof I affix my signature, in presence of two witnesses.

JAMES C. MEEM.
